PIN-UP LAMP

Filed April 28, 1952

FIG. I

FIG. II

FIG. III

Raymond L. Springer
INVENTOR.

UNITED STATES PATENT OFFICE

168,718

PIN-UP LAMP

Raymond L. Springer, Cincinnati, Ohio

Application April 28, 1952, Serial No. 19,510

Term of patent 14 years

(Cl. D48—4)

To all whom it may concern:

Be it known that I, Raymond L. Springer, a citizen of the United States, residing at Cincinnati, in the county of Hamilton and State of Ohio, have invented a new, original, and ornamental Design for Pin-Up Lamp, of which the following is a specification, reference being had to the accompanying drawing, forming a part hereof.

I claim:

The ornamental design for a pin-up lamp, as shown.

RAYMOND L. SPRINGER.
